PORTABLE REFRIGERATING DEVICE

Leonard F. Clerc, Chicago, Ill.

Application November 16, 1942, Serial No. 465,655

5 Claims. (Cl. 62—91.5)

This invention relates to refrigerating devices, and has particular reference to a portable refrigerator, which employs solid carbon dioxide or "dry ice" as the refrigerant.

An object of the invention is to provide a portable domestic refrigerating device of the character referred to, which may be used in small apartments, trailers, boats and the like.

Another object of the invention is to provide a portable domestic refrigerator which is inexpensive to manufacture, light in weight, and one which can be manufactured without using critical materials needed in the war effort.

Another object of the invention is the provision of a compact, portable refrigerator which employs "dry ice" as the refrigerant, and has a wet ice compartment for making ice cubes, which compartment is readily accessible from the exterior of the structure.

Another object of the invention is the provision of a portable refrigerating device, which is constructed in two separate sections, whereby the individual sections may be interchanged with other sections to effect increased utility.

Another object of the invention is the provision of a refrigerating device of the character mentioned, which is constructed in separable sections and is provided with a removable cooling control assembly, which is mounted between, and is secured in position by the said separable sections.

The foregoing and other objects and advantages of the invention will appear as the description proceeds, reference being made from time to time to the accompanying drawings in which:

Fig. 1 is a perspective view of a device embodying my invention.

Fig. 2 is a sectional view taken substantially on the line 2—2 of Fig. 1.

Fig. 3 is a sectional view taken substantially on the line 3—3 of Fig. 1.

Fig. 4 is a modified form of the device.

Fig. 5 is a perspective view of the control assembly.

Referring now more particularly to the drawings it will be understood that in the embodiment herein disclosed, my device consists of a trunk like structure comprising an upper section 5, and a lower section 6, each being made of a tough fibrous material, reinforced at the corners and edges as at 7, and secured together with trunk locks 8.

Each section 5 and 6 (Figs. 2 and 3) is lined with double layers of insulating pads 9, which are constructed and assembled as disclosed in my co-pending application S. N. 441,431, filed May 2, 55

1942. The pads 9 are covered with canvas and are waterproofed and secured in place by marine glue or similar means.

The lower section 6 has a door 10 which opens into the storage compartment 11 (Figs. 2 and 3) and the upper section 5 has a door 12, which opens into the "dry ice" compartment 13. A smaller door 14 also opens into the "dry ice" compartment 13, through which the wet ice trays 15 are inserted and removed.

Interposed between the sections 5 and 6 (Figs. 2 and 3) is a control assembly 16, which is fully disclosed and claimed in my co-pending application Serial Number 465,656, filed November 16, 1942. The control assembly 16 forms no part of this invention, except as it is herein combined with the other elements of my device.

Broadly the control assembly 16 consists of several apertured layers of a plastic material arranged so that one layer 16A may be moved relatively to the others, so that the apertures may be moved into and out of alignment, whereby the flow of CO₂ gas from the "dry ice" compartment may be controlled. The control assembly 16 is supported at either end in offsets 17 formed in the liners 9 of the lower section 6, and is held against upward displacement by the liners 9 of the upper section 5.

The control assembly 16 is provided on top with a spaced platform 18, which serves as a support for the "dry ice." And from the bottom of the assembly 16 there depends a plastic baffle 19, which serves to evenly diffuse the CO₂ gas which escapes through the apertures of the control assembly 16. The wet ice trays 15 rest on the assembly 16, and are held in position by the guides 20, which are secured to the under side of the platform 18.

Secured to the inside surface of the liners 9, 40 in spaced relation as at 21, are panels 22, which are adapted to provide air spaces for the circulation of air and CO₂ gas. The side and back panels 22, of both sections 5 and 6, extend to the control assembly 16, and the control assembly 16 is provided with additional apertures as at 23A, to permit the warmer air from the lower section 6 to pass through the control assembly 16 and enter the upper section 5, back of the panels 22. This functions as follows:

As the cold CO₂ gas enters the lower section 6 through the apertures in the control assembly 16, the warmer air will be caused to rise back of the panels 22, and will pass through the apertures 23 in the assembly 16 and will enter the upper section 5, back of the panels 22, and will

spill over the top of the panels 22 on to the top of the "dry ice." This will effect a perfect circulation of the air and CO₂ gas between the sections 5 and 6 and will insure more effective refrigeration.

The control assembly 16 is adjusted by means of a control lever 24, which is accessible through the door 10 of the lower section 6.

In Fig. 4, I have shown a modified form of the device. In this embodiment the lower section 6A is identical with the lower section 6 of Fig. 1.

The upper section 5A, however, is modified in that the refrigerant compartment 26 is smaller and there is a compartment 27 and a compartment 28 at either side thereof. The compartment 27 in this embodiment is used for ice trays 29, and the compartment 28 is used to hold frozen foods 30, or the like.

The control mechanism 31 is similar to that disclosed in Figs. 1, 2 and 3, and functions as described previously. The "dry ice" platform 32 in this instance is lower than shown in the previous views, but functions the same.

In this embodiment the compartments 27 and 28 are provided with passageways 33 at the top and similar ones at the bottom which communicate with the refrigerant compartment 26, so that these compartments may be maintained at a much lower temperature than is desired for the general storage compartment in the lower section 6A.

The compartments 27 and 28 are closed by the hinged doors 34 and 35 through which the compartments are accessible from the exterior.

Having described my invention, what I claim and desire to secure by Letters Patent is:

1. The combination of upper and lower insu-

lated sections, separated by an adjustable apertured control panel, said panel and said upper section being supported by the walls of said lower section, spaced means carried by said panel for supporting a solid refrigerant such as "dry ice," and spaced means carried below said panel for uniformly diffusing the gas produced by the sublimation of said solid refrigerant.

2. The combination of upper and lower separable insulated sections, separated by an adjustable apertured control panel, spaced means carried on said panel for supporting a solid refrigerant such as "dry ice," spaced means carried below said panel for uniformly diffusing the gas produced by the sublimation of said solid refrigerant, and panels spaced from the inside walls of said sections, and adapted to provide air spaces back of said panels, said air spaces being positioned so as to communicate with marginal apertures formed in said control panel.

3. The combination defined in claim 1, including means for securing said sections and said panel in predetermined relation.

4. The combination defined in claim 1, in which said control panel is arranged to support water ice trays, below said first named spaced means.

5. The combination defined in claim 1, in which said control panel is arranged to support water ice trays, below said first named spaced means, and there being an opening in the wall of said upper section arranged to permit said water ice trays to be removed without disturbing the contents of either said upper section or said lower section.

LEONARD F. CLERC.
